ATTORNEYS.

UNITED STATES PATENT OFFICE.

CHERUBINO NANNINI, OF MANHATTAN, NEVADA.

HAIR CLIPPER.

Application filed May 29, 1922. Serial No. 564,417.

To all whom it may concern:

Be it known that I, CHERUBINO NANNINI, a citizen of the United States, and a resident of Manhattan, county of Nye, and 5 State of Nevada, have invented a new and useful Hair Clipper, of which the following is a specification.

My invention relates in general to hair clippers as commonly used by barbers and 10 has reference more particularly to means which may be considered in the nature of an attachment to enable the clippers to be used for cutting relatively long hair, whereas as heretofore the clippers have been only 15 applicable to clipping short hair.

As an example of the use of clippers equipped with the invention, it might be pointed out that as at present practiced clippers are usually used around the neck and 20 discarded in favor of shears when the hair on the side and top of the head is to be trimmed. With my improved means certain adjustments may be realized which will enable the clippers, as above stated, to be used 25 for cutting the hair all over the head without the necessity of using shears. The attachment will enable the clippers to be used not only by barbers but also enable anyone 30 to cut their own hair with every degree of satisfaction.

The illustrative embodiment of the invention is shown in the accompanying drawing, in which Figure 1 is a plan view of a conventional type of hair clipper illustrating 35 the application of my invention; Figure 2 is a view in side elevation of the cutting head of the clipper showing my invention as applied thereto; Figure 3 is an enlarged view in cross section on the line 3—3 of Figure 2; Figure 4 is a view in cross section 40 on the line 4—4 of Figure 3, and Figure 5 is a bottom plan view of a clipper head showing a part of my invention as applied thereto.

45 Referring now to the drawing in detail, "A" represents a clipper having the customary fixed cutting blade (5) and the slidably mounted cutting blade (6). It is of course known that the blade (6) is moved back and forth over the blade (5) by the 50 handles of the clipper to produce the required cutting effect between the teeth of the cutters. According to my invention I propose to mount a plate (7) beneath the 55 fixed cutting blade (5) with the dimensions

of the plate substantially corresponding to the dimensions of the blade (5). The plate is made with a plurality of teeth (8), the ends of which being turned upwardly as best shown in Figure 4. The length of the teeth (8) is longer than the teeth of the blade (5). To guide or direct the hair to be clipped to the blades (5) and (6), I prefer to hinge a guide strip (9) to the plate (7) at the commencement of the teeth (8). 60 This guide strip is positioned transversely across the plate (7) and the outer free edge of the same terminates in relatively short teeth (9'). Normally the guide strip lies flush with the plate (7) but when the clippers are being used the hair will push the same up against the under side of the blade (5), as best shown in Figure 4.

The important feature of the invention resides in adjusting the plates (7) in spaced 75 relation relative to the blade (5) according to the desired cutting effect to be accomplished. For instance, to clip the hair long the plate (7) will be moved further away from the blade (5) than if the hair is to 80 be clipped short. This effect is obvious.

To realize a suitable mounting for the plate (7) as well as to accomplish the various adjustments of the same as stated, I prefer to provide openings through the clipper 85 including the crown (11) with the openings made to receive the upstanding posts (12) and (13), the same extending through these openings in the clipper and protruding a suitable distance above the same. Arranged 90 on each face of the posts (12) and (13) is a rack (14). Riveted, brazed or otherwise fixed upon the crown (11) of the clippers is a housing (15), the same having openings in its top through which the posts (12) and (13) are protruded. Arranged transversely 95 across the rack faces of the posts is a shaft (16), the same having a bearing in opposite ends of the housing (15) and carrying pinions (17) and (18), one for each of the 100 racks (14). The one end of the shaft (16) has a turn knob or the like (19) which enables the shaft (16) to be rotated, and since the pinions (17) and (18) are flush with the racks (14) the rotation of the shaft (16) 105 will move the posts up and down, which will in turn move the plate (7) to and from spaced relation to the blade (5) for realizing the adjustment previously referred to. 110 In order to hold the predetermined adjust-

ment of the plate (7) relatively of the blade (5) I propose to use a key (20), the same being slidably mounted on the under side of the top of the housing (15) and having 5 a knob or the like (21) fixed thereto by a pin (22), which extends through an opening in the top of the housing and enables the key to be slid to and from engagement with the racks (14).

10 By turning the thumb knob (19) the pinions will move the posts and in turn the plate (7) to effect proper adjustment, and when the adjustment is made it may be held by throwing the key (20) in engagement 15 with the racks (14). To hold the key in engagement with the racks it is suggested to use a spring strip (23), see Figure 1, so that the key is maintained under the influence of the spring and in engagement with the 20 racks.

I claim:

1. In a hair clipper having a fixed and slidably movable cutting blade, means positioned beneath the fixed blade adapted to be moved to and from the same for adjusting the cutting effect of the blades, and comprising a plate having a plurality of teeth corresponding to the lower cutting blade, upstanding posts on said blade, openings 25 through the clipper made to receive said posts, each of said posts having a rack face, a transverse shaft mounted across said rack faces, pinions on said shaft meshing with said rack faces, and means for rotating said 30 shaft whereby the said plate may be adjustably moved to and from the lower cutting blade by raising or lowering said posts.

2. In a hair clipper having a fixed and slidably movable cutting blade, means positioned beneath the fixed blade adapted to be moved to and from the same for adjusting the cutting effect of the blades, and comprising a plate having a plurality of teeth corresponding to the lower cutting 45 blade, upstanding posts on said blade, openings through the clipper made to receive said posts, each of said posts having a rack face, a transverse shaft mounted across said rack faces, pinions on said shaft meshing 50 with said rack faces, means for rotating said shaft whereby the said plate may be adjustably moved to and from the lower cutting blade by raising or lowering said posts, and a housing upon the top of the 55 clipper through which the posts extend, said shaft and pinions being housed within said housing, and means for locking the posts to hold an adjustment of the plate.

3. In a hair clipper having a fixed and 60 slidably movable cutting blade, means positioned beneath the fixed blade adapted to be moved to and from the same for adjusting the cutting effect of the blades, comprising a plate having a plurality of teeth corresponding to the lower cutting 65 blade,

blade, upstanding posts on said blade, openings through the clipper made to receive said posts, each of said posts having a rack face, a transverse shaft mounted across said rack faces, pinions on said shaft meshing with said rack faces, means for rotating said shaft whereby the said plate may be adjustably moved to and from the lower cutting blade by raising or lowering said posts, a housing upon the top of the 70 clipper through which the posts extend, said shaft and pinions being housed within said housing, and means for locking the posts to hold an adjustment of the plate comprising a key slidably mounted in the 75 housing and a knob on the key extending outside the housing for moving the key into and out of engagement with the rack faces on the posts.

4. In a hair clipper having a fixed and 80 slidably movable cutting blade, means positioned beneath the fixed blade adapted to be moved to and from the same for adjusting the cutting effect of the blades, comprising a plate having a plurality of teeth, upstanding posts on the plate extending through the clipper, means upon the top of the clipper co-operating with said posts for affecting said adjustment of the plate, and a hinged guide strip on the plate for directing the hair to be cut to the cutting blades. 85

5. In a hair clipper having a fixed and 90 slidably movable cutting blade, means positioned beneath the fixed blade adapted to be moved to and from the same for adjusting the cutting effect of the blades, comprising a plate having a plurality of teeth corresponding to the lower cutting blade, mounting means for the plate extending 95 through the clipper, means upon the top of the clipper co-operating with said mounting means for effecting said adjustment of the plate, and a hinged guide strip on the plate for directing the hair to be cut to the cutting blades. 100

6. In a hair clipper having a fixed and 105 slidably movable cutting blade, means positioned beneath the fixed blade adapted to be moved to and from the same for adjusting the cutting effect of the blades, comprising a plate having a plurality of teeth corresponding to the lower cutting blade, upstanding posts on said blade, openings 110 through the clipper made to receive said posts, each of said posts having a rack face, a transverse shaft mounted across said rack face, pinions on said shaft meshing with said rack faces, means for rotating said shaft whereby the said plate may be adjustably moved to and from the lower cutting blade by raising or lowering said posts, a housing upon the top of the clipper through which the posts extend, said shaft and pinions being housed within said housing, means for locking the posts to hold an ad- 115 120 125 130

justment of the plate, and a hinged guide strip on the plate for directing the hair to be cut to the cutting blades.

7. In a hair clipper having a fixed and 5 slidably movable cutting blade, means positioned beneath the fixed blade adapted to be moved to and from the same for adjusting the cutting effect of the blades, comprising a plate having a plurality of teeth corre- 10 sponding to the lower cutting blade, up- standing posts on said blade, openings through the clipper made to receive said posts, each of said posts having a rack face, 15 faces, pinions on said shaft meshing with said rack faces, means for rotating said shaft

whereby the said plate may be adjustably moved to and from the lower cutting blade by raising or lowering said posts, a housing upon the top of the clipper through which 20 the posts extend, said shaft and pinions being housed within said housing, means for locking the posts to hold an adjustment of the plate comprising a key slidably mounted in the housing, a knob on the key ex- 25 tends outside the housing for moving the key into and out of engagement with the rack faces on the posts, and a hinged guide strip on the plate for directing the hair to be cut to the cutting blades.

CHERUBINO NANNINI.
